(57) **CLAIM**

I claim the ornamental design for the wheelchair brake and attachment bracket.

DESCRIPTION

FIG. 1 is an isometric view from the upper left rear of the wheelchair brake and accompanying attachment bracket of the invention;

FIG. 2 is an elevation of the right side thereof;

FIG. 3 is an elevation of the left side thereof;

FIG. 4 is a front elevation thereof;

FIG. 5 is a rear elevation thereof;

FIG. 6 is a top view thereof;

FIG. 7 is a bottom view thereof;

FIG. 8 is an isometric view of the wheelchair brake similar to that shown in FIG. 1 mounted upon a wheel of a wheelchair shown in dashed lines to illustrate a typical arrangement on a wheelchair; and,

FIG. 9 is an isometric view of the bracket attachment shown in previous views with an alternative brake construction shown in dashed lines mounted thereupon.
